Fig. 5

Fig. 4

FIG. 1 is a perspective view of a pull for a slide fastener showing our new design;

FIG. 2 is a plan view of one of the two identical sides of the pull for a slide fastener as shown in FIG. 1;

FIG. 3 is a side view of the same;

FIG. 4 is a top end view of the same; and

FIG. 5 is a bottom end view of the same.

The broken line showing of a slider for a slide fastener is for illustrative purposes only.

The characteristic features of our design reside in the appearance of the lower portion of the pull for a slide fastener containing two opposed ridges and a recessed circular hole therebelow the walls forming the hole being beveled and both faces of the entire pull being beveled on the edges all as shown.

We claim:

The ornamental design for a pull for a slide fastener, substantially as shown and described.
